(57) **CLAIM**

We claim the ornamental design for a radio remote control unit, as shown and described.

DESCRIPTION

The design of the present application is directed to a radio remote control unit for remotely controlling an object such as a toy airplane, boat, car or other propelled device.

FIG. 1 is a front elevational view of a radio remote control unit showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front side perspective view thereof;

FIG. 8 is a rear side perspective view thereof; and,

FIG. 9 is a perspective view thereof in which the antenna thereof is extended.
